US00D506645S

(12) **United States Design Patent** (10) Patent No.: **US D506,645 S**
(45) Date of Patent: **** Jun. 28, 2005**

(54) **COOLER**

(75) Inventors: **Richard C. Bellofatto, Jr.**, Peabody, MA (US); **Mark T. Salander**, Barrington, RI (US); **Quincy L. Reese**, Brockton, MA (US)

(73) Assignee: **The Gem Group**, Lawrence, MA (US)

(**) Term: **14 Years**

(21) Appl. No.: **29/195,936**

(22) Filed: **Dec. 18, 2003**

(51) LOC (8) Cl. **07-01**

(52) U.S. Cl. **D7/607**
